UNITED STATES PATENT OFFICE.

WILLIAM A. BRADEN, OF CHICAGO, ILLINOIS.

TRACK CONSTRUCTION.

No. 893,134.

Specification of Letters Patent. Patented July 14, 1908.

Application filed September 14, 1907. Serial No. 392,871.

To all whom it may concern:

Be it known that I, WILLIAM A. BRADEN, a citizen of the United States, residing at Chicago, in the county of Cook and State of Illinois, have invented certain new and useful Improvements in Track Constructions, of which the following is a specification.

My invention relates to track construction and particularly to that type wherein stiffening sections are employed beneath and parallel to the rails. The invention has for its principal objects; the provision of improved and simplified means for securing the rails and stiffening sections rigidly in their proper relative positions; the provision of improved means for maintaining the opposing rails in parallelism independent of the ties; and the provision of a simple and efficient form of tie to coöperate with the track construction and assist in anchoring the rails to the road bed. Certain specific embodiments of the invention are illustrated in the accompanying drawings, wherein:

Figure 1 is a transverse section through one form of track construction,

Figure 2 is a transverse section through a slightly modified form of track construction,

Figure 3 is a section through the ties taken on the lines III—III of Figure 2, and shows the principal part of the track construction in side elevation,

Figure 4 is an enlarged detail cross section through one side of the track construction,

Figure 5 is a side elevation of the structure shown in Figure 4,

Figure 6 is a longitudinal section of the securing means on the line VI—VI of Figure 5,

Figure 7 is a side elevation of the tie employed with the rails shown in section thereon,

Figure 8 is a longitudinal section taken through the tie of Figure 7,

Figure 9 is a plan view of the tie,

Figure 10 is an enlarged transverse detail section on the line X—X of Figure 8, the clamping member 21 being removed, and

Figure 11 is an enlarged detail section through a modified form of track construction.

Referring first to the form of device as shown in cross section in Figure 1, 1—1 are the rails, 2—2 are the stiffening sections beneath and parallel to the rails 1—1, which sections are preferably in the form of a bulb

or deck beams as shown, and 3 are the ties which are preferably of the hollow pressed steel construction shown in Figures 7 to 10 inclusive and to be more particularly described hereinafter. The rails 1—1 and beams 2—2 on each side of the track are held securely in fixed relation to each other by means of opposing clamping members 4, which clamping members as shown are shaped to fit the flanges of the members 1 and 2, and are spaced along the track at short intervals as indicated in Figure 3. In order to hold the two sides of the track construction in fixed relation with respect to each other and also to clamp the members 4—4 together the tube 5 and rod 6 are provided. The rod is preferably threaded at both ends, and the clamping members are pressed up tightly against the ends of the tubes by means of the nuts 7 placed on the threaded ends of the rod 6. By this means one side of the track construction is supported and steadied from the other side, and the ties are not depended upon to hold the rails in parallelism, and if desired, little or no securing means need be provided for securing the rails to the ties. In the form of construction shown in Figure 1, the fish plates 8 for securing the rails together at their ends, are made independent of the clamps 4—4. In the form of construction shown in Figure 2, the fish plates 8' are made integral with the clamping members 4—4, and the members 4 are provided with downwardly projecting ears 9 through which the bolt 10 is passed. The fish plate portions 8' are secured by means of the bolts 11 as shown in Figure 3. The joint 12 of Fig. 3 is secured by means of the independent fish plates, while the joint to the right is secured by means of the fish plates 8' integral with the clamps. The ends of adjacent beams 2 are secured together by means of the strap 14 (Figure 3), which strap is secured by means of the bolts 15. In the enlarged detail construction as shown in Figures 4, 5 and 6, the rod construction is slightly changed in that the rod is provided at one end with an integral head 7' instead of having nuts at both ends as in the construction shown in Figure 1. The construction of the tie is shown in Figures 7, 8, 9 and 10, and as here shown the tie comprises a pressed steel bottom sheet 16.

provided with up-turned edges 17. The bottom sheet is corrugated as shown at 18 in order to give a better grip upon the road bed, and the ends are curved down as shown at 5 19 for a similar purpose. As indicated in Figure 9, the ends of the tie are flared, and the up-turned edges 17 taper down to the bottom sheet at such end portions, giving the tie the contour shown in side elevation in 10 Figure 7. In order to provide a seat for the rail, the lips 20 are pressed down from the up-turned edges 17, thus providing for the seating of the rail in the upper surface of the tie and at the same time giving an enlarged 15 bearing surface for the bottom of the rail. In order to prevent longitudinal movement of the rail with respect to the tie, the clamps 21 are provided inside the tie. These clamps 21 are of a length equal to the width of the 20 tie, and are securely fastened to the rail flange and to the lips 20 by means of the cross bolts 22. In order to provide a more extended bearing surface for the clamps 21, the liners 23 (Fig. 10) are inserted beneath 25 the lips 20. It will be observed that by this arrangement the rail is not only prevented from moving longitudinally with respect to the tie, but is secured against vertical movement by virtue of the engagement of the 30 clamps 21 with the lips 20.

In Figure 11 a modified form of track construction is shown. As here shown, the rail 1 and stiffening sections 2 are spaced apart by means of the eye-bar 24, and all the parts 35 are clamped together by means of the clip members 25, and transverse bolts 26. This arrangement also prevents longitudinal movement of the rail with respect to the ties, as the end of the member 24 and the ends of 40 the clip 25 bear against the sides of the ties and thus hold the parts in position.

Having thus described my invention and illustrated its use, what I claim as new and desire to secure by Letters Patent is the following:

1. The combination with rails, parallel flanged stiffening sections therebeneath; and interposed ties, of spacing and securing means comprising pairs of opposing clamps 50 between and engaging the ties, each clamp adapted to fit one side of a rail flange and one side of a stiffening section flange and means for securing the clamps against the said flanges.

55 2. The combination with a rail, flanged stiffening sections beneath and paralleling the rail; and interposed ties, of means for securing the rail to the section comprising two opposing clamps each having means for engaging the flanges of the rail and stiffening section and each provided with a web turned to meet the other beneath the web of the rail, and means for securing the inturned webs together.

3. The combination with rails, and parallel flanged stiffening sections therebeneath, of spacing and securing means comprising a pair of opposing clamps adjacent the ends of the rails and each adapted to fit one side of a rail flange and web and one side of a stiffening section flange and web, bolts for securing the clamps against the said flanges and webs, and other bolts through the webs of the stiffening section and the clamps for securing the parts in position. 75

4. The combination with a track comprising a pair of parallel rails, of a parallel stiffening section beneath each rail, interposed ties, spacing members between the rails and stiffening sections for securing such parts together, and means extending transversely across the track between the spacing members for holding them in fixed relative position. 80

5. The combination with a track comprising a pair of parallel rails, of a parallel stiffening section beneath each rail, interposed ties, spacing members between the rails and stiffening sections for securing such parts together, tube members extending between the spacing members on opposite sides of the track, and bolts extending through the tubes and the spacing members for holding such spacing members against the ends of the tubes. 85

6. The combination with a track comprising a pair of parallel rails, a stiffening section parallel to each rail and interposed ties, of clamping means for securing the rails to the stiffening sections comprising pairs of opposing clamps each adapted to fit one side of the rail flange and one side of a stiffening section flange, and means for securing the clamps together and for holding the clamps on opposite sides of the track in fixed relation, comprising transverse tubes abutting the clamps 100 on opposite sides of the track, and bolts extending through the clamps and tubes for holding the clamps against the ends of the tubes. 105

7. A securing means for tracks comprising a pair of clamps each made in two sections and adapted to secure a rail to a parallel flanged stiffening section, a tube extending between the clamps, and a bolt extending through the tube and the two sections of each 115 clamp whereby the clamp sections are secured together and the two clamps held against the opposite ends of the tube.

8. In combination, the two pairs of half clamps 4, 4 each pair adapted to secure a rail and stiffening section parallel thereto together, a tube 5 extending between the inner half clamps, and the rod 6 provided with the nut 7 for securing the parts together. 120

9. The combination with a hollow tie recessed transversely for the reception of a rail, of a rail seated in the recess, a stiffening section beneath the tie and parallel to the rail 125

and means intermediate the ties for clamping the rail to the stiffening section.

10. The combination with a track comprising rails, parallel flanged stiffening sections and interposed ties, of clamping members interposed between the ties and engaging the flanges of the rails and stiffening sections.

In testimony whereof I have hereunto signed my name in the presence of the two 10 subscribed witnesses.

WILLIAM A. BRADEN.
